PULLEY

Ellis I. Toder, 9225 Grace Lane,
Philadelphia, Pa. 19115

Filed Mar. 28, 1969, Ser. No. 16,495

Term of patent 14 years

Int. Cl. D8—03

U.S. Cl. D8—216

Fig. 3.

Fig. 4.

Fig. 5.

Fig. 6.
Fig. 8.Fig. 7.

Fig. 9

FIG. 1 is a perspective view from above of my new design of the pulley in opened out flat form;

FIG. 2 is a perspective view of my new design of the pulley in folded up assembled form;

FIG. 3 is a side elevational view of my new design of the pulley as would be seen when viewed along line 3-3 of FIG. 1;

FIG. 4 is a top plan view of my new design of the pulley as would be seen when viewed along line 4-4 of FIG. 3;

FIG. 5 is a bottom plan view of my new design of the pulley as would be seen when viewed along line 5-5 of FIG. 3;

FIG. 6 is an end elevation of my new design of the pulley as would be seen when viewed along the line 6-6 of FIG. 3, the view from the opposite end being the same;

FIG. 7 is an end elevation of my new design of the pulley as would be seen when viewed along the line 7-7 of FIG. 2;

FIG. 8 is a side elevational view of my new design of the pulley as would be seen when viewed along line 8-8 of FIG. 7;

FIG. 9 is a top plan view of my new design of the pulley as would be seen when viewed along line 9-9 of FIG. 7;

FIG. 10 is a bottom plan view of my new design of the pulley as would be seen when viewed along line 10-10 of FIG. 7;

FIG. 11 is a partial vertical sectional view, on an enlarged scale, of my new design of the pulley as would be seen when viewed along line 11-11 of FIG. 8;

FIG. 12 is a side elevation showing the pulley bottom-installed to an underlying surface nail, with the surface, nail and pulley cord in phantom for illustrative purposes only;

FIG. 13 is a side elevation showing the pulley side-installed to a vertical surface with the surface and pulley cord in phantom for illustrative purposes only.

I claim:

The ornamental design for a pulley, as shown and described.
